UNITED STATES PATENT OFFICE.

ARTHUR V. DICKEY, OF SEATTLE, WASHINGTON.

AIR-GUN.

1,146,753.

Specification of Letters Patent. Patented July 13, 1915.

Application filed June 19, 1913. Serial No. 774,559.

To all whom it may concern:

Be it known that I, ARTHUR V. DICKEY, a citizen of the United States, residing at Seattle, in the county of King and State of Washington, have invented certain new and useful Improvements in Air-Guns, of which the following is a specification.

This invention relates to air-guns of the type described and illustrated in United States Patent No. 1,026,303, issued to me May 14, 1912. Its object is the perfecting of such guns to render the same more efficient, more compact, the various operable parts more durable and easy of access, and generally, to provide an air-gun which will have a more extended use than hitherto.

The invention consists, more particularly, in the improved construction of, and novel devices for, actuating the breech-block, and in the employment of safety appliances to uncock the gun and likewise prevent the accidental discharge of the same.

The invention further consists in the novel construction and combination of various other features which contribute to the efficiency of the gun.

The invention is illustrated in the accompanying drawings, wherein—

Figure 1 is a vertical longitudinal section of an air-gun embodying the present invention in its preferred form. Fig. 2 is a horizontal sectional view of a portion of the same. Fig. 3 is a transverse vertical section through 3—3 of Figs. 1 and 2. Fig. 4 is a fragmentary longitudinal vertical section of the gun from the opposite side to which it is shown in Fig. 1. Fig. 5 is an enlarged longitudinal sectional view of the pump-barrel shown detached. Fig. 6 is a perspective view of the breech-block. Fig. 7 is a similar view of the breech-block shifting-lever. Fig. 8 is a like view of the reciprocating actuator for the breech-block lever. Fig. 9 is a perspective view of the trigger lock. Fig. 10 is a longitudinal vertical sectional view illustrating modified construction of the breech-block, its operating mechanism and associated parts of the gun. Figs. 11 and 12 are transverse sectional views through 11—11 and 12—12, respectively, of Fig. 10. Fig. 13 is a perspective view of the breech-block shifting-pin shown in Fig. 10. Fig. 14 is a perspective view of the actuator for the shifting-pin shown in the preceding view.

Similarly to the gun shown in the aforesaid patent, and referring to Figs. 1 to 9,

this invention is provided with a frame 1 to which are secured the gun-barrel 2 and the stock 3. The rear end of the barrel is socketed in a member 4 which is chambered, as at 5, to receive the breech-block 6. Communication is had by a passage 7 arranged to be in alinement with the barrel-bore, between the chamber 5 and an air-receiver 8 which is communicatively connected by a duct 9 with an air-reservoir 10.

At its inlet end, the passage 7 is provided with a seat for a valve 11 which is yieldingly held in closed position by a spring 12.

13 represents a pump cylinder communicating from its rear end by a duct 14 with the reservoir 10. A spring-pressed non-return valve 15 is utilized to prevent any return flow of air from the reservoir. Said pump-cylinder is desirably positioned in the stock of the gun. The pump plunger 16 is operated through the agency of a piston-rod 17 which is connected by a link 18 with a lever 19. The latter is hingedly connected at its forward end to the gun-frame 1 against which it is laid when unemployed and serves as a pump-handle for operating the plunger 16.

An improvement to the pump consists in having the piston-rod where it extends through the plunger, of less diameter than the bore 20 (Fig. 5) to thereby afford an air passage through the plunger. At one side of the plunger, the rod is provided with a collar 21 and a plate 22 is secured to the rod at the other side. Said plate and collar are spaced apart a distance greater than the thickness of the plunger so that there will be lost motion to the piston-rod at the beginning of each stroke before the collar or plate encounter the plunger to subsequently pull or push the plunger. When the piston-rod is thus moved independently of the plunger, air is free to flow through the latter to afford a supply for compressing after the plunger has reached the ends of its successive strokes and during the beginning of the following movements of the piston-rod.

To the rear of the member 4 is a tubular casing 23 within which is a removable tube 24 which serves as the magazine for the projectiles P. This magazine is secured in place as by a bayonet-joint comprising a pin 25 (Fig. 2) engaging in a slot 26 provided in the casing 23. Within the magazine is a cylindrical follower 27 which is yieldingly pressed toward the open front end of the

tube by means of a helical spring 28 and whereby the projectiles are pressed forwardly to be supplied to the breech-block 6. The aforesaid breech-block, as best shown in Figs. 2, 3 and 6, consists of a cylindrical plug having an aperture or pocket 29 extending diametrically therethrough. Such pocket is positioned so as to be presented to the magazine to receive a projectile when the block is in one position and also when the block has been shifted into the position in which it is represented in Fig. 2 the pocket will be brought into alignment with the barrel-bore and with the discharge end of the air-passage 7. Said block is provided with a branch 30 which extends into an opening provided in the member 4. The branch 30 is formed with a notch 31 (see Fig. 6) to receive the arm 32 of a lever 33 which is fulcrumed intermediate its length to a pivotal pin 34. The other arm 35 of said lever is provided with a stud 36 which is engaged in a cam-slot 37 provided in the top portion 38 of an actuator (Fig. 8) which is connected to the gun-frame for longitudinal reciprocatory movements. The slot 37 is arranged so that the actuator, upon being thrust forwardly, will cause the breech-block to be shifted to present the pocket thereof into position to receive a projectile from the magazine, and when the actuator is moved in the contrary direction, the cam-slot will effect the movement of the breech-block to present the pocket in line with the barrel-bore.

Below the gun-barrel is a tube 39 containing the main-spring 40 adapted to urge a hammer-block 41 rearwardly against an extension 42 of the valve 11 to unseat the latter when the hammer-block becomes operative.

Rigidly secured to and extending through the hammer block is a pin 43 whose ends protrude through longitudinal slots provided in the tube 39. Extending downwardly from the actuator part 38 and between the side flanges 44 thereof is a finger 38' whose office is to engage the pin 43 when the actuator is thrust forward to effect the forward travel of the hammer-block and the compression of the spring 40. When the hammer-block has been thus moved forward, it is engaged by the latch-arm 45 of a bell-crank lever through the agency of a spring 46. The other arm 47 of this lever is connected by a pull-rod 48 with a trigger 49 fulcrumed to a pivotal pin 50.

To lock the trigger so that it may be rendered temporarily inoperative to effect the release of the hammer-block, I provide a safety device consisting of a bell-crank lever, (Fig. 9) having an arm 51 arranged to be swung against the trigger, as shown in Fig. 1, through the instrumentality of the other arm or finger-piece 52. The arm 50 is formed with flat faces 53 disposed in rectangular relations with each other and furnish seats

against which a leaf-spring 54 bears to prevent the accidental movement of the safety device when the same is set in operative or inoperative positions with respect to the trigger.

In operation, the actuator is thrust forward, as above explained, to shift the breech-block into position to receive a projectile and likewise cause the hammer-block to be carried into engaged position with the latch-arm 45; the actuator is then retracted to shift the breech-block so that the projectile will be brought into position to be discharged. Oftentimes, however, it is desirable to uncock the gun by returning the hammer-block to its rearmost or inoperative position without discharging the projectile. To this end, I provide a slider attachment comprising a bar 55 movable longitudinally in guides 56 and is arranged to have its front end contact with the hammer-block pin 43 when the slider is pushed forward, as by a lug 57 provided on the rear end of the bar.

To employ the slider to return the hammer-block to its rearmost position, the slider is first pushed forward by the operator against the pin 43, whereupon the latch-arm 45 is withdrawn from the hammer-block by pulling the trigger 49. The hammer-block thus released is pushed by the main spring 40 against the slider which is allowed to slowly recede with the hammer-block in opposition to a thumb pressure applied by the operator against the lug 57.

Referring now to the modifications illustrated in Figs. 10 to 14, inclusive, the breech-block is operated by an oscillatory rod 60 having a bit 61 which engages within the notch 31 of the block-branch 30. The rod 60 is mounted in suitable supports, such as 62, provided on the gun-frame or parts which are rigid therewith and extends through a hole 63 provided in a longitudinally slideable actuator 64. Said actuator serves as a nut with respect to said rod, the latter being formed with a screw-thread or a fin 65, as shown, which fits within a helical groove 66 extending from the hole 63. As represented, the actuator is provided with guideways 67 and 68 which receive the gun-barrel 1 and the tube 39 to co-act therewith to obviate any rotary movement to the actuator when moved back and forth in the performance of its function.

Like the aforescribed actuator, the actuator 64 is provided with a downwardly directed finger 38² which serves to engage the hammer-block pin 43 when the actuator is thrust forward.

In operation, the actuator 64, in being pushed forward, effects a partial rotation to the rod 60 to swing the bit 61 in such a manner as to cause the breech-block to be moved into position to receive a projectile and also

cause the hammer-block to be carried into operative position. When the actuator is pulled back, the breech-block is effected to carry the projectile into position to be discharged.

The invention will, it is believed, be understood from the foregoing description.

What I claim, is—

1. In an air-gun, the combination with the projectile magazine, the gun-barrel, a reservoir for fluid under pressure, a duct connecting said reservoir with the barrel, a valve for said connection, a spring-pressed hammer-block for opening said valve, a breech-block, a longitudinally-disposed vibrating device engaging the breech block, an actuator for turning said device to move said breech-block into operative position and for operating the hammer-block, means for engaging said hammer-block in its operative position, trigger devices for disengaging the last named means from the hammer-block, and means for rendering said trigger-means temporarily inoperative.
  2. In an air-gun, the combination with the projectile magazine, the gun-barrel, a reservoir for fluid under pressure, a duct connecting said reservoir with the barrel, a valve for said connection, a spring-pressed hammer-block for opening said valve, a breech-block, means for moving said hammer-block into operative position and operating the breech-block, comprising a member having a projection to engage the breech-block, and an actuator for turning said member, means for engaging said hammer-block in its operative position, trigger devices for disengaging the last named means from the hammer-block, and means coöperating with said trigger-devices whereby the hammer-block may be moved into inoperative position without influencing said valve.
  3. In an air-gun, the combination with
- the projectile magazine, the gun-barrel, a reservoir for fluid under pressure, a duct connecting said reservoir with the barrel, a valve for said connection, a spring-pressed hammer-block for opening said valve, a breech-block, a vibratory device connected with said breech-block, a longitudinally-movable actuator for moving said hammer-block into operative position and operating the breech-block through said device, means for engaging said hammer-block in its operative position, trigger devices for disengaging the last named means from the hammer-block, means for rendering said trigger-means temporarily inoperative, and means coöperating with said trigger devices whereby the hammer-block may be moved into inoperative position without influencing said valve.
4. In an air-gun, the combination with the gun-barrel, an air-reservoir communicating with said barrel, a valve for said communication, a spring-impelled hammer-block for opening the valve, trigger-controlled devices for releasably securing the hammer-block in operative position, a breech-block, a vibrating device engaging said breech-block, and an actuator for operating the breech-block through said device and for conveying the hammer-block into position to be engaged by said trigger-controlled devices, of means acting supplementary to said devices whereby the hammer-block may be moved into inoperative position without affecting either the breech-block or said valve.

Signed at Seattle, Wash., this 6th day of June, 1913.

ARTHUR V. DICKEY.
